UNITED STATES PATENT OFFICE

DE WITT C. GRAY, OF RAHWAY, NEW JERSEY.

ADDING AND RECORDING MACHINE.

No. 926,738.

Specification of Letters Patent.

Patented July 6, 1909.

Application filed April 25, 1908. Serial No. 429,123.

To all whom it may concern:

Be it known that I, DE WITT C. GRAY, a citizen of the United States, and residing at Rahway, in the county of Union and State of New Jersey, have invented certain new and useful Improvements in Adding and Recording Machines, of which the following is a specification, such as will enable those skilled in the art to which it appertains to make and

use the same.

This invention relates to adding and recording machines, and the object thereof is to provide a machine that will make a record of separate transactions and record whenever desired the total of such transactions, and also provide means whereby the said total can be ascertained without operating the means for recording the said total; and with these and other objects in view the invention consists in a machine of the class specified constructed as hereinafter described and claimed.

The invention is fully disclosed in the following specification, of which the accompanying drawings form a part, in which the separate parts of my improvement are designated by suitable reference characters in each of the views, and in which:

Figure 1 is a plan view of my improved machine with the front portion thereof broken away; Fig. 2 a longitudinal vertical section on the line 2—2 of Fig. 3; Fig. 3 a view similar to Fig. 1 but showing the top removed together with the parts of the machine carried by the top; Fig. 4 a transverse vertical section on the line 4—4 of Fig. 2; Fig. 5 a transverse vertical section on the line 5—5 of Fig. 2; Fig. 6 a transverse vertical section on the line 6—6 of Fig. 2; Fig. 7 a longitudinal vertical sectional view on the line 7—7 of Fig. 3 but showing only certain details of the construction; Fig. 8 a partial section on the line 8—8 of Fig. 4; Fig. 9 a partial horizontal section on the line 9—9 of Fig. 4; Fig. 10 a partial longitudinal vertical section on the line 10—10 of Fig. 4 and indicating some of the parts only in dotted lines; Fig. 11 a section on the line 11—11 of Fig. 4; Fig. 12 a section on the line 11—11 of Fig. 4 but looking inwardly, or in a direction opposite to that of Fig. 11; Fig. 13 a face view of a ratchet and reading wheel forming part of the total adding mechanism; Fig. 14 a side view of the wheel shown in Fig. 13; Fig. 15 a vertical section of the wheel shown in Figs.

13 and 14; Fig. 16 a transverse section of a printing and recording wheel forming part of the total adding mechanism; Fig. 17 a side view of the wheel shown in Fig. 16; Fig. 18 a face view of the wheel shown in Figs. 16 and 17; Fig. 19 a face view of a ratchet wheel provided with a grooved hub and used in connection with the wheels shown in Figs. 13 to 18 inclusive; Fig. 20 a side view of the wheel shown in Fig. 19; Fig. 21 a side view of a pawl used in connection with the wheel shown in Fig. 14, and also shown in said figure; Fig. 22 an inside edge view of the pawl shown in Fig. 21; Fig. 23 a side view of a cam which in practice is mounted on the shaft 70 which carries the wheels shown in Figs. 13 to 18 inclusive and forms part of the total adding mechanism; Fig. 24 a section of the cam shown in Fig. 23; Fig. 25 a face view of a printing wheel forming part of the item recording mechanism; Fig. 26 a side view of said wheel, and—Fig. 27 a diagrammatic side view of a modification of the item recording mechanism.

In the practice of my invention, I provide an oblong case *a*, the top *a*² of which is hinged at the front end of the case as shown at *a*³ and the front end portion of the top *a*² is substantially of the same vertical depth as the bottom front end portion of said case, as clearly indicated in Fig. 2, while the depth of the top *a*² of the case through the central and rear end portion thereof is much less than the depth of the corresponding part of the bottom portion of the case.

In my improvement part of the elements of the machine are mounted in the movable top *a*² of the case, and the rest in the bottom part of said case, and the principal parts of the adding and recording mechanism are mounted in the movable top *a*². This facilitates the assembling of the parts of the machine and the care thereof; and I will first describe the parts of the machine that are mounted in the movable top *a*².

The top part *a*² of the case is provided with a longitudinal opening *a*⁴ which extends approximately the full length thereof except at the front end thereof, and the central and front end portion of said opening is covered by a spring metal plate *a*⁵ the front end of which is secured at *a*⁶ and the rear end of which is provided with backwardly directed spring tongues *a*⁷ the rear ends of which are provided with hook members *a*⁸ which open

downwardly, and said spring plate a^5 is provided midway of its length with transversely arranged eight apertures a^9 .

Between the rear end portion of the spring 5 metal plate a^5 , or the hook members a^8 and the rear end portion of the top part a^2 of the case, is an open space b , as shown in Figs. 1 and 2, the same constituting the rear end portion of the longitudinal opening a^4 , and 10 beneath which is a counter-sunk shelf or support b^2 as shown in Figs. 2 and 6, on which is mounted a plurality of longitudinal movable ratchet bars b^3 which are nine in number, in the construction shown, and said bars are 15 separated by longitudinal partitions b^4 , as shown in Fig. 6, and formed integrally with the counter-sunk shelf or support b^2 .

The rear end portions of the ratchet bars b^3 are provided in their upper faces with 20 ratchet teeth b^5 which are numbered from zero to nine from front to back as clearly shown in Fig. 1, and connected with the said bars forwardly of the counter-sunk shelf or support b^2 , and with the rear wall of the top 25 a^2 of the case, are springs b^6 which normally hold said bars at the limit of their backward movement as shown in Fig. 2, and in contact with buffer spring fingers b^7 connected with a plate b^8 secured to the rear end wall of the 30 top a^2 of the case as shown in Figs. 2 and 6.

The rear end portions of the bars b^3 which contain the ratchet teeth b^5 are rectangular in cross section, but the front end portions of said bars are T-shaped in cross section as 35 shown in Fig. 4, and the bottom edges or faces thereof are provided with ratchet teeth b^9 which are ten in number. Mounted transversely of the top a^2 of the case and immediately under the rear end portions of the 40 ratchet bars b^3 when in their normal position as shown in Fig. 2 is a shaft c which I will call the item shaft, and said shaft is carried by inwardly directed bosses c^2 as shown in Fig. 5 through which are passed screws c^3 , the inner 45 ends of which form supports for the shaft c .

Mounted on the shaft c and rotatable thereon independently of each other is a plurality of item recording wheels c^4 , as shown in Fig. 5, and one of which is shown on an enlarged scale in Fig. 25, and each of which is 50 provided on one side with a gear c^5 , and each of the wheels c^4 is provided on the face thereof with numerals from zero to nine.

The front end portions of the ratchet bars 55 b^3 pass between the wheels c^4 as shown in Fig. 5, and pivoted to each of said bars centrally thereof as shown at c^6 in Fig. 2 is a rack bar c^7 , and these rack bars c^7 which are shown in Figs. 2 and 4 rest on the gears c^5 of the 60 wheels c^4 .

Mounted in the top a^2 of the case in front of the shaft c and parallel therewith is another shaft d which, for the purpose of this description, I will call the total adder. This 65 shaft is supported at one end by an inwardly

directed boss d^2 and at the opposite end by a removable tubular bearing d^3 provided at its outer end with a head d^4 which is countersunk in and secured in the right side of the top a^2 of the case, as clearly shown in Fig. 4. 70

The shaft d is provided within the bearing d^2 with a tubular bushing d^5 , and the outer end thereof is provided with a knob or handle e which is shown in section in Fig. 8, and in full lines in Fig. 4. Rigidly secured to the 75 shaft d and corresponding in position with the rack bars b^3 are cam disks f part of which are shown in Fig. 4, and one of which is shown in Fig. 10, and one of which is shown in detail in Figs. 23 and 24, and these cam 80 disks are provided at one side with a shoulder f^2 adjacent to which is a concavity or depression f^3 , and between the cam disks f on the shaft d are placed sleeves f^4 .

Mounted between each of the cam disks f 85 and on the sleeves f^4 are ratchet wheels f^5 provided with hubs f^6 having in the ends thereof annular recesses f^7 , and the said hubs are also provided with grooves f^8 . One of the ratchet wheels f^5 is clearly shown in Figs. 90 19 and 20, and a part of said wheels are shown in Fig. 4 in section, and one of said wheels is also shown in Fig. 10.

Mounted on the hubs f^6 of the ratchet wheels f^5 are total adder recording wheels g , 95 part of which are shown in full lines, and part in section in Fig. 4, and one of which is shown in detail in Figs. 16 to 18 inclusive, and one of which is also shown in Fig. 2, and these wheels are provided with numerals from zero 100 to nine inclusive, and said wheels are cut out annularly on one side thereof as shown at g^2 to receive the ratchet wheels f^5 as clearly shown in Fig. 4, and said wheels are provided with ribs or feathers g^3 which enter the 105 grooves f^8 in the hubs f^6 of the ratchet wheels f^5 . There are also mounted between the cam disks f and adjacent to the wheels g eight total adder wheels g^4 which are also cut out annularly of one side thereof as shown at g^5 110 in Figs. 4, 14 and 15, and these wheels are shown partly in full lines and partly in section in Fig. 4, and one of them is shown in detail in Figs. 13 to 15 inclusive, and one is also indicated in dotted lines in Figs. 2 115 and 10.

In the annular cut out portion g^5 of the wheels g^4 are pivoted pawls g^6 having short arms g^7 and longer arms g^8 , and the short arms g^7 are provided with laterally directed 120 fingers h which bear on the faces of the cam disks f , and in the grooves or annular recesses f^7 of the hubs f^6 , and hold the fingers h^2 in contact with the face of the cam disks f . The wheels g^4 are ratchet wheels and are provided with ten teeth which correspond with the ratchet teeth b^9 in the bottom faces of the front end portions of the ratchet bars b^3 , and the teeth on the wheels g^4 are numbered from 125 zero to nine as clearly indicated in Fig. 14, 130

and these numbers, in practice, are read through the apertures or openings a^9 in the spring top plate a^5 of the top a^2 of the case.

In Fig. 14 the numbers from zero to nine are placed around the wheel in order to indicate the normal position of said wheels when the parts of the total adder mechanism are set ready to begin operation; and in Fig. 17 the numbers are shown around the wheel for a similar purpose, and it will be seen from these two figures that the numbers on these two wheels are, in practice, arranged just opposite, the zero mark being at the bottom of the wheel g , and at the top of the wheel g^4 .

15 Mounted forwardly of the shaft d and parallel therewith is a rod h^3 on which are mounted a plurality of dogs h^4 , which equal in number the total adder wheels g^4 , and forwardly of the shaft h is a transverse support h^5 having backwardly directed spring fingers h^6 as shown in Fig. 2. The dogs h^4 are provided with rearwardly directed noses which operate in connection with the wheels g^4 and with forwardly directed noses on which the spring fingers h^6 bear, and the dogs h^4 prevent the reverse movement of the wheels g , g^4 and f^6 .

Mounted in the front end portion of the case and removable when the top a^2 is open, is a paper roll h^7 on which is wound a sheet or strip h^8 of paper, and this sheet or strip is carried upwardly and passed around a guide roller i as shown in Figs. 2 and 3, and said sheet or strip is then carried backwardly and passed between rollers i^2 and i^3 . The roller i^2 is mounted in the top a^2 of the case, while the roller i^3 is mounted in the bottom portion of the case, and in the form of construction shown, the roller i^2 is a flexible roller, and the roller i^3 is provided with a corrugated surface as shown in Figs. 3 and 7, and these rollers serve as feed rollers as hereinafter described, and from these rollers the sheet or strip h^8 of paper passes backwardly and is passed out through a suitable aperture i^4 between the top a^2 and bottom part of the case and may be torn off by means of a cutter i^5 .

Secured to the inner side of the opposite sides of the top a^2 of the case as clearly shown in Fig. 2 are plates j which depend into the bottom part of the case when the top a^2 is closed, and these plates at each side carry two spools j^2 , said spools being arranged in pairs transversely of the case. Secured in the plates j are hollow bosses j^3 on which the spools j^2 are mounted and rotate, and passed through the sides of the bottom of the case are screws j^4 having heads j^5 by which they may be manipulated, and these screws hold the spools j^2 on the bosses j^3 .

60 Secured centrally of the plates j are inwardly directed posts j^6 on which are mounted yoke-shaped members j^8 having forwardly and backwardly directed spring arms j^9 , and these spring arms j^9 normally bear on the inner face of the corresponding

spools j^2 and normally prevent said spools from racing, and mounted on the posts j^8 are spiral springs k which force the yoke-shaped members j^8 outwardly.

In order to take the spools j^2 out, the screws j^4 are taken out and the top a^2 of the case is opened and the yoke-shaped devices j^8 may be drawn inwardly as shown in dotted lines in Fig. 9, and the spools detached from the bosses j^3 . As hereinbefore stated 75 the spools j^2 are arranged in pairs transversely of the case, and in practice, each pair of spools is provided with an ordinary carbon ribbon k^2 similar to the ribbons employed in typewriting machines, and these 80 ribbons are preferably of different colors, and in practice these ribbons are also passed transversely of and over the sheet or strip h^8 of paper as shown in Figs. 2 and 5, and in order to move these ribbons transversely of 85 the sheet or strip h^8 of paper in the operation of the machine, the screws j^4 are manipulated to turn the spools j^2 , or one spool of each pair, and in this way the ribbons may be drawn from one spool of each pair 90 onto the other whenever desired.

Mounted transversely of the rear end portion of the case is a shaft k^3 with which is connected a pair of arms k^4 which range forwardly and are curved upwardly at their front ends and with which is connected a transversely ranging impression hammer k^5 which is adapted to operate on and beneath the sheet or strip h^8 of paper at the point where the ribbon k^2 of the rear pair of spools 100 j^2 passes thereover, and this point is directly under the item shaft c and the wheels c^4 mounted thereon as clearly shown in Fig. 2.

Mounted transversely of the bottom portion of the case and in the right hand side 105 thereof, in the form of construction shown, and approximately under the shaft d is a rotary stub shaft k^6 with which is connected an arm k^7 which extends downwardly and rearwardly and is also connected at k^8 with 110 a yoke-shaped link member k^9 which is connected with the arms k^4 at k^{10} , and connected with the outer end of the rotary stub shaft k^6 is a key arm m provided with an "item" key m^2 by means of which the arms 115 k^4 may be thrown upwardly into the position shown in Fig. 2, and connected with one or both of the arms k^4 is a contractile spring m^3 which is also secured to the bottom of the case, and by means of which the 120 arms k^4 are drawn downwardly after each operation of the key m^2 as hereinafter described.

The shaft k^3 is also provided with two trip lugs m^4 having shoulders m^5 as clearly 125 shown in Fig. 7, and pivoted at m^6 within the opposite side walls of the top a^2 of the case and forwardly of the shaft k^3 when said top is closed are rocking arms m^7 to the rear ends of which are pivoted trip arms n pro- 130

vided with cam surfaces n^2 in connection with which the trip lugs m^4 operate, and said trip arms are provided with noses n^3 adapted to engage the shoulders m^5 of the trip lugs m^4 , and springs n^4 are connected with the trip arms n and bear on pins secured to the rock arms m^7 and serve to force the lower ends of the trip arms n backwardly so as to cause them to engage the lugs m^4 .

Pivoted to the front ends of the rock arms m^5 is a yoke-member m^8 as clearly shown in Figs. 1, 2 and 6, and the cross head portion of the yoke member m^8 ranges transversely 15 and above the ratchet bars b^3 and is engaged by the hook members a^8 at the rear ends of the spring tongues a^7 of the spring metal plate a . Mounted transversely of and in the rear end portion of the bottom of 20 the case and forwardly of the shaft k^3 is a shaft o with which is connected a pair of arms o^2 similar to the arms k^4 and which range downwardly and forwardly and the front ends of which are curved upwardly 25 and carry an impression hammer o^3 which ranges transversely of the machine and which is adapted to be thrown into contact with the bottom of the sheet or strip h^8 of paper directly beneath the point where the front carbon ribbon k^2 passes thereover, and directly beneath the total adder shaft d , and the wheels g and g^4 mounted thereon as clearly shown in Fig. 2. Rearwardly of the 30 rotary stub shaft k^6 and secured in the same side of the bottom portion of the case is another rotary stub shaft o^4 with which is connected an arm o^5 similar to the arm k^7 and which ranges downwardly and backwardly 35 and is connected at o^6 with a yoke-shaped link device o^7 , the sides of which are connected with the arms o^2 and connected with the outer end of the rotary stub shaft o^4 is a key arm o^8 with which is connected a "total" key o^9 .

Connected with the bottom of the case, and in the left hand side portion thereof as shown in Figs. 2, 3 and 5 are uprights p and p^2 , the upright p being arranged forwardly of the upright p^2 , and said uprights are provided at their upper ends with backwardly directed stops p^3 adapted to engage the corresponding ends of the transversely ranging supports p^4 of the impression hammers k^5 and o^3 , and the object of this construction is 50 to prevent the twisting or wrenching of said impression hammers when only the right hand wheels g and g^4 on the shaft d are in operation, and the corresponding wheels c^4 on the shaft c are in operation, or in other 55 words when only small amounts are to be counted and recorded.

The bottom feed roller i^3 between which and the roller i^2 the sheet or strip h^8 of paper is passed is provided at its right hand end 60 with a ratchet wheel p^5 , and mounted on the

shaft of said roller at said end is an arm p^6 with which is connected a link p^7 , with which is pivotally connected a pawl p^8 which operates in connection with the ratchet p^5 , and a spring p^9 is secured to said link and bears on 70 said pawl.

The shaft k^3 is provided with a rigid arm r with which the link p^7 is pivotally connected, and in the operation of the machine as hereinafter described the movement of the shaft 75 k^3 operates the roller i^3 and feeds the sheet or strip h^8 of paper backwardly through the machine.

The total adder shaft d passes through the bearing d^2 as hereinbefore described, and into 80 the knob or handle e as shown in Fig. 8, and said knob or handle is provided with a chamber r^2 through which is passed a screw r^3 which is screwed into the shaft d , and placed in the chamber or recess r^2 is a spring r^4 which 85 bears on the head of the screw r^3 and against the inner end wall of the chamber r^2 .

The end of the shaft d which passes through the bearing d^2 and into the knob or handle e is also provided in its opposite sides 90 with longitudinal grooves r^5 which receive corresponding ribs or feathers r^6 on the knob or handle e . The outer face or head of the bearing d^2 is provided, as shown in Fig. 12, with a segmental cam lug r^7 adjacent to 95 which and spaced therefrom is a lug or projection r^8 , and the knob or handle e is provided with a circular head s , as clearly shown in Figs. 4 and 11, on the face of which is a pin s^2 which operates on the cam lug r^7 and 100 between said cam lug and the lug or projection r^8 , in the operation of the machine as hereinafter described.

The plates j which carry the ribbon spools j^2 are provided at their upper edges with inwardly directed flanges j^3 in which are formed slits j^4 through which the ribbons k^2 are passed, in which operation said ribbons are given a quarter turn and a right angle bend, so that they may be carried parallel 110 with and beneath the shafts c and d .

The top a^2 of the case, and the bottom part thereof are provided at their rear ends with spring catch devices t by which the top may be held in a closed position, and these 115 catch devices consist, in the form of construction shown, of triangular lugs t^2 secured to the inner side walls of the top a^2 of the case and spring arms t^3 secured to the bottom of the case at t^4 , and the free ends of which 120 range upwardly and are adapted to engage the triangular lugs t^2 , as shown at t^5 , and said springs are provided with press buttons t^6 which pass through the side walls of the bottom of the case, and by means of which the 125 spring arms t^3 may be forced inwardly so as to disengage the same from the triangular lugs t^2 , and permit the top of the case to be opened.

Mounted on the pivotal supports m^6 of the 130

rock arms m^7 is a yoke-shaped device u which ranges transversely of and above the ratchet bars b^3 rearwardly of the yoke-shaped device m^8 , and the object of which is 5 to form a stop for a pencil, tool or other instrument used in forcing the rack bars b^3 forwardly in the operation of the machine as hereinafter described.

The item wheels c^4 are provided at regular 10 intervals with radial projections u^2 on which the numerals are placed, and these radial projections are equally spaced except at one side where there is a blank space u^3 formed by leaving out one of the radial projections 15 u^2 , and this blank space u^3 is between the zero and the numeral nine, and in assembling the parts of the machine for use the item wheels c^4 are placed on the shaft c , with the blank space u^3 down, and in this operation 20 the recording total adder wheels g are placed on the shaft d in such manner that the zero marks thereon will be down, while the sight total adder wheels g^4 are so placed on said shaft that the zero marks will be up. 25 The operation will be readily understood from the foregoing description, when taken in connection with the accompanying drawings and the following statement thereof.

The operator stands or sits at the front of 30 the machine with the "total" and "item" keys at his right. The item recording wheels mounted on the time shaft are placed on said shaft so that the blank spaces u^3 are all down and perfectly alined, and the total adder recording wheels are placed on the total adder shaft so that all of the zeros are down and in 35 perfect alinement, while the sight total adder wheels are placed on said last named shaft so that the zeros are all up and perfectly alined.

40 The operator being careful to place the paper and ribbons properly or as shown in Fig. 2. An ordinary pencil or other instrument may be employed to operate the ratchet bars through the open space b in the top of 45 the top casing a^2 . Now for illustration if it be desired to record 432.19 the pencil or instrument is placed behind the shoulder formed by the ratchet tooth, having the numeral 8 on its face, of the ratchet bar at the 50 extreme right of the series of ratchet bars exposed through the opening b of the casing. This bar is drawn forward or toward the operator until the pencil or instrument comes in contact with the transverse stop u , the 55 hook a^8 of the spring tongue a^7 corresponding to said bar snaps or rides over the teeth of the bar until the tooth carrying the numeral 9 reaches the stop u , when the bar will be locked at this point by the hook a^8 .

60 The pencil or instrument is now placed over the 1 in the next bar to the left and is drawn forward until the pencil reaches the stop u ; the next bar to the left is operated by placing the pencil or instrument over the 2 and drawing said bar forward and the next

bar to the left is operated by placing the pencil or instrument over the numeral 3 and drawing the bar forward while the next bar to the left is operated by placing the pencil or instrument over the numeral 4, and drawing said bar forward until the pencil comes in contact with the stop u . 70

These operations by reason of the rack bars c^7 engaging the gear wheels c^6 and the ratchet teeth b^9 engaging the teeth of the 75 sight total adder wheels g^4 , manipulate the item recorder wheels, the sight total adder wheels and the recording total adder wheels so that the numerals 432.19 appear at the bottom of the time wheels over the ribbon 80 and paper, while the numerals 432.19 appear at the top of the sight total adder wheels and at the bottom of the recording total adder wheels over the ribbon and paper. The operator now depresses the item key which 85 operates the impression hammer k^5 to make an impression on the strip of paper h^8 , and after the impression is made and the time key released the impression hammer is drawn downwardly by the spring m^3 , and this downward movement causes the shoulders m^5 on the shaft k^3 to engage the noses n^3 of the trip arms n , drawing said arms downwardly and thus rocking the arm m^7 on its pivot, and the 90 forward end of said arm raises the yoke member m^8 , and this operation raises the rear ends of the spring tongues a^7 and disengages the hooks a^8 from the teeth of the ratchet bars b^3 and allows them to be drawn rearwardly by the springs b^6 and the parts are 95 again ready to be operated.

During the upward movement of the impression hammer k^5 the arm r carried on the shaft k^3 operates the feed roller i^3 through the link p^7 and feeds the strip of paper rearwardly. The total adder wheels remain in the position hereinbefore described, by reason of the dogs h^4 and springs h^6 holding them, and the teeth b^9 of the ratchet bars b^3 ride over the teeth of the sight total adder 100 wheels when the bars are drawn rearwardly by the springs b^6 .

When the yoke member m^8 has been raised sufficiently to release the hooks from the ratchet bars, the trip lugs m^4 operate against the cam faces n^2 of the trip arms n to throw the shoulders m^5 out of engagement with the noses n^3 , and this allows the spring tongues a^7 to force the yoke member m^8 downwardly 110 to return the rock arms m^7 and trip arms n to their normal positions.

It will be understood that at each operation of a ratchet bar, a sight total adder wheel and a recording total adder wheel are operated in addition to an item recording wheel, and it will also be understood that all of the total adder wheels remain stationary while the ratchet bars are returning to their normal position while the item recording 125 wheels are rotated during both the forward 130

and backward movement of the ratchet bars by reason of the rack bars c^7 being in constant engagement with the gear wheels e^8 .

When it is desired to know the total of a number of items the amount will appear at the top of the eight total adder wheels and can be plainly read through the openings a^9 in the top of the casing and when it is desired to record said total; the "total" key is operated to impress said amount on the strip of paper. The ribbon ranging under the numerals carried by the item recording wheels is preferably blue, while the ribbon ranging under the numerals of the total adder recording wheels is preferably red so that a "total" can easily be distinguished from an "item".

In the total adding mechanism the operation, except the "setting" is automatic. The four members between each cam disk on the total adder shaft viz:—the eight total adder wheel, the recording total adder wheel, the ratchet f^5 and the pawl g^6 are so assembled that they form a single element or unit of the total adding mechanism, and the pin h carried by the pawl g^6 of one element or unit range to the left, and rides on the cam disk f and overlies the teeth of the ratchet f^5 comprising a part of the next element or unit to the left, and by reason of this construction the pin h of the pawl g^6 operates to give the element or unit next to the left a step movement at each rotation of the element or unit at its right. This is accomplished by the pin h when it rides down into the depression f^3 of the cam disk and engages with a tooth of the ratchet f^5 of the next element or unit to the left, as clearly shown in Fig. 10. During the operation of the total adding mechanism the pin s^2 of the knob or handle e , lies in the recess formed by the cam lug r^7 and lug r^8 thus locking the shaft d against rotation.

When it is desired to reset the total adder mechanism, the knob or handle e is pulled out against the action of the spring r^4 , until the pin s^2 clears the lugs r^7 and r^8 , the knob or handle e is then turned to the left until the pin comes in contact with the lug r^8 , this operation turns the cams so that the shoulders f^2 contact with the pins h of the pawls g^6 , thus carrying all of the elements or units back to their normal or starting position. When this operation is completed the knob or handle is then turned to the left until the pin s^2 rides up on the cam lug r^7 and is pulled into the recess between said cam lug and the lug r^8 when the shaft is locked and the parts ready for operation.

In Fig. 27 I have shown a modified form of item recording mechanism in which I employ wheels having abbreviations of the names of the months of the year, wheels having numerals designed to record the days of the months, and wheels having letters which enable me to record the name of a firm or corporation in addition to nine wheels having

numbers to record the amount of an item or transaction. This construction will be applicable to adding and recording machines, where more detail is required. I employ in this construction a shaft v on which is mounted from left to right a month wheel v^2 , day wheels v^3 , lettered wheels v^4 and numbered wheels v^5 , all of said wheels carry gear wheels v^6 and are adapted to rotate independently on said shaft. 75

Having fully described my invention, what I claim as new and desire to secure by Letters Patent, is:—

1. In an adding and recording machine, a casing provided with a movable top, said top part being provided with an opening, recording wheels mounted in the top part, sliding devices adapted to be operated through the opening in the top part of the casing and to operate said wheels, means for feeding a strip of paper through the casing beneath the recording wheels, devices mounted in the bottom part of the casing and co-acting with said wheels for making an impression on said paper, and means for operating said devices. 80 90

2. In an adding and recording machine, a casing provided with a movable top having an opening therein, two gangs of wheels mounted in said top and provided with printing faces, means for feeding a strip of paper through said casing below said wheels, devices mounted in the bottom part of the casing and co-acting with one gang of wheels to record items, other devices mounted in the bottom part of the casing and co-acting with the other gang of wheels to record totals, means for operating said devices, and sliding devices mounted in the top part of the casing and adapted to be operated through the opening therein and to operate said wheels. 95 100 105

3. In an adding and recording machine, a casing provided with a movable top having an opening therein, two gangs of printing wheels mounted in said top, means for feeding a strip of paper through said machine beneath said wheels, devices mounted in the bottom part of the casing and co-acting with one gang of wheels to record items, other devices mounted in the bottom part of the casing and co-acting with the wheels of the other gang to record totals, and sliding devices mounted horizontally over said wheels in the top part of the casing and adapted to operate said wheels and to be operated through the opening in said top part of the casing. 110 115 120

4. In an adding and printing machine, a casing provided with a top having an opening therein, means for feeding a strip of paper through said casing and giving the same an intermittent movement, two gangs of printing wheels mounted in said casing, sliding devices adapted to operate said wheels and to be operated through the opening in the top of the casing, means for holding said sliding devices in operative position, and means co- 125 130

acting with said wheels for making an impression on said paper.

5. In an adding and printing machine, a casing provided with a top having an opening 5 therein, means for feeding a strip of paper through said casing and giving the same an intermittent movement, two gangs of printing wheels mounted in said casing, sliding devices adapted to operate said wheels and to 10 be operated through the opening in the top of the casing, means for holding said sliding devices in operative position, and means co-acting with said printing wheels for making an impression on said paper, said last named 15 means comprising impression hammers ranging across the casing and under said gangs of wheels.

6. In an adding and recording machine, a casing, two gangs of wheels mounted therein, 20 sliding devices mounted in said casing and adapted to rotate said wheels, one gang of wheels being composed of alternate reading and printing wheels, the other gang being composed of alternate printing and ratchet 25 wheels, means for feeding a strip of paper through said casing and under said wheels, and means co-acting with said wheels for making impressions on said paper.

7. In an adding and recording machine, a 30 casing, two gangs of printing wheels mounted therein, sliding devices adapted to operate said wheels, one gang of wheels being adapted to print items and the other gang being adapted to print totals, means for feeding a 35 strip of paper through the machine, two hammers mounted in said casing, one of said hammers coacting in common with one gang of wheels, and the other hammer coacting in common with the other gang of wheels to 40 make impressions on a strip of paper.

8. In an adding and recording machine, a casing, two gangs of printing wheels mounted therein, sliding devices adapted to operate said wheels, one gang of wheels being adapted 45 to print items and the other gang being adapted to print totals, two hammers mounted in said casing, one of said hammers coacting in common with one gang of wheels and the other hammer coacting in common 50 with the other gang of wheels to make impressions on a strip of paper as it is fed through the machine, means for holding said sliding devices in operative position, means for releasing said sliding devices, and means 55 for returning said sliding devices to the normal or inoperative position.

9. In an adding and recording machine, a casing, means for feeding a strip of paper therethrough, two gangs of printing wheels 60 mounted therein, reading wheels being arranged alternately with printing wheels in one of said gangs, sliding devices for operating said wheels, two rock shafts mounted transversely of said casing, hammers mounted 65 on said shafts and adapted to coact with

said wheels to make impressions on said paper, means for holding said sliding devices in an inoperative position, means carried by one of said shafts to release said sliding devices, and means for returning said sliding 70 devices to their normal or inoperative positions.

10. In an adding and recording machine, a casing provided with a movable top having an opening therein, printing wheels mounted 75 in the top part of the casing, sliding devices mounted in the top part of the casing and adapted to be operated through the opening therein and to operate said wheels, means for feeding a strip of paper through said casing below said wheels and giving it an intermittent movement, and hammer devices mounted in the bottom part of the casing and co-acting with said wheels to make impressions on said paper.

11. In an adding and recording machine, a casing provided with a top having an opening therein, means for feeding a strip of paper through said casing and giving it an intermittent movement, two gangs of printing 90 wheels mounted in said casing, means co-acting with one gang of said wheels to record items, means co-acting with the other gang of wheels to record totals, means for displaying said totals through the top of the casing, 95 and sliding devices horizontally movable over said wheels and adapted to be operated through the opening in the top of the casing and to rotate said wheels.

12. An adding and recording machine provided with two gangs of wheels, one gang of said wheels being composed of alternate gears and printing wheels, and the other gang of wheels being composed of alternate printing and ratchet wheels, said ratchet wheels serving also as reading wheels.

13. In a printing and recording machine, a casing provided with a movable top having an opening therein and two gangs of wheels mounted in said movable top, one of said 110 gangs of wheels being composed of alternate gear and printing wheels, and the other gang of wheels being composed of alternate printing and ratchet wheels, the ratchet wheels being also adapted to serve as reading wheels, 115 and the top of the casing being provided with transverse openings through which the reading wheels may be seen.

14. In a printing and recording machine, a casing provided with a movable top having 120 an opening therein and two gangs of wheels mounted in said movable top, one of said gangs of wheels being composed of alternate gear and printing wheels, and the other gang of wheels being composed of alternate printing and ratchet wheels, the ratchet wheels 125 being also adapted to serve as reading wheels, and the top of the casing being provided with transverse openings through which the reading wheels may be seen, the top of said casing 130

being also provided with sliding devices which when moved in one direction are adapted to operate the wheels of both gangs in the same direction, and when moved in the 5 opposite direction to reverse the movement of the wheels of the first named gang and return them to their normal position in which operation the wheels of the last named gang are held stationary.

10 15. In an adding and printing machine, a casing, means for feeding a strip of paper therethrough and giving the same an intermittent movement, two gangs of printing wheels, sliding devices adapted to operate 15 said wheels, means for holding said sliding devices in operative position, tension devices for returning said sliding devices to their normal position, devices co-acting with said wheels for making an impression on said paper, and means controlled by said devices for releasing the sliding devices and allowing them to be returned to their normal or inoperative position by said tension devices.

16. In an adding and recording machine, a 25 casing, two gangs of printing wheels mounted in the top part of the casing, means for feeding a strip of paper through said casing below said wheels, means for supporting strips of carbon paper in the casing and feeding the same transversely thereof beneath said gangs of wheels and beneath said paper, means for operating said wheels, devices mounted in the bottom part of the machine and co-acting with one gang of wheels to record 30 items, other devices mounted in the bottom part of the machine and co-acting with the other gang of wheels to record totals, and sliding devices mounted in the top part of the machine and operated through an opening 35 formed therein and adapted to operate said wheels.

17. In an adding and recording machine, a casing provided with a movable top in which are mounted two transverse gangs of 45 printing wheels, said top being provided at the opposite sides thereof with plates which depend into the bottom part of the casing when the top is closed, spools supported by said plates, said spools being adapted to support strips of carbon tape, means for feeding said strips of tape transversely of the case and beneath said gangs of wheels, means for feeding a strip of paper beneath said gangs of wheels, devices for operating said wheels, 50 and hammer devices mounted in the bottom of the casing and co-acting with said wheels to form impressions on said strip of paper, said spools being also removable from their supports and provided with tensional brake 55 devices which also operate to hold them in position.

18. In an adding and recording machine, a case provided with a movable top having an opening therein, means for feeding a strip 60 of paper through said case, two gangs of

printing wheels mounted in said case, means co-acting with the wheels of one gang to record items, means co-acting with the wheels of the other gang to record totals, and sliding devices horizontally movable over 70 said wheels and adapted to rotate the same, said sliding devices being provided with ratchet teeth having numerals thereon adapted to be read through the opening in the top of the case. 75

19. In an adding and recording machine, a case provided with a movable top having an opening therein, means for feeding a strip of paper through said case, two gangs of printing wheels mounted in said case, 80 means co-acting with the wheels of one gang to record items, means co-acting with the wheels of the other gang to record totals, and sliding devices horizontally movable over said wheels and adapted to rotate the same, 85 said sliding devices being provided with ratchet teeth having numerals thereon adapted to be read through the opening in the top of the case, and said sliding devices being adapted to be operated in one direction through the opening in the top of the case and being provided with tensional devices for moving them in the opposite direction, and spring devices connected with the top of the case and operating in connection 90 with the said ratchet teeth for holding said sliding devices against the operation of said spring devices. 95

20. In an adding and recording machine, a casing, means for feeding a strip of paper therethrough, two gangs of printing wheels provided with printing faces, means co-acting with the printing wheels of one gang to record items, means co-acting with the printing wheels of the other gang to record 100 totals, and sliding devices adapted to rotate said wheels, said sliding devices being provided with ratchet teeth on which are placed numerals, springs for moving said sliding devices in one direction, and spring catches operating in connection with said ratchet teeth to hold said sliding devices against the operation of said springs. 110

21. In a machine of the class described, two gangs of wheels, sliding bars provided with ratchet teeth adapted to operate the wheels of one gang in one direction, and rack bars pivoted to the sliding bars and adapted to operate the wheels of the other gang in both directions. 115

22. In a machine of the class described, two gangs of wheels, sliding bars provided with ratchet teeth adapted to operate the wheels of one gang in one direction, and rack bars pivoted to the sliding bars and adapted 120 to operate the wheels of the other gang in both directions, said sliding bars being also provided with another set of ratchet teeth having numerals thereon. 125

23. In an adding and recording machine, 130

- a case provided with a movable top, two gangs of printing wheels mounted transversely in said top, pivoted hammer arms mounted in the bottom part of the casing 5 and adapted to swing in vertical planes and provided with supports carrying hammers adapted to operate in connection with said wheels, stop devices adapted to engage said supports, means for feeding a strip of paper 10 through the machine beneath said wheels, means for supporting and feeding strips of carbon transversely of the machine and beneath said gangs of wheels, and means for operating said wheels.
- 15 24. A machine of the class described provided with sliding bars having ratchet teeth provided with numerals, springs for moving said sliding bars in one direction, spring catch devices adapted to engage said teeth 20 and hold said bars against the operation of said springs, and tripping devices for disengaging said spring catch devices from said ratchet teeth.

25. In an adding and recording machine, two gangs of printing wheels mounted transversely thereof, two pivoted hammer devices mounted beneath said gangs of wheels, one of which operates in connection with the wheels of one gang, and the other in connection with the wheels of the other gang, means 25 for feeding a strip of paper through the machine between said gangs of wheels and said hammer devices, means for feeding strips of carbon transversely of the machine and over each of said hammer devices, means for operating 30 said hammer devices, and means for operating said wheels.

In testimony that I claim the foregoing as my invention I have signed my name in presence of the subscribing witnesses this 23rd day of April 1908.
